UNITED STATES PATENT OFFICE.

GEORGE H. RIDDELL, OF BUFFALO, NEW YORK, ASSIGNOR TO DOMESTIC SEWING MACHINE CO., INC., OF BUFFALO, NEW YORK, A CORPORATION OF NEW YORK.

BOBBIN-WINDER FOR MOTOR-DRIVEN SEWING-MACHINES.

1,351,442.

Specification of Letters Patent. Patented Aug. 31, 1920.

Application filed September 26, 1919. Serial No. 326,619.

To all whom it may concern:

Be it known that I, GEORGE H. RIDDELL, a citizen of the United States, residing at Buffalo, county of Erie, State of New York, have invented a certain new and useful Improvement in Bobbin-Winders for Motor-Driven Sewing-Machines, and declare the following to be a full, clear, and exact description of the same, such as will enable others skilled in the art to which it pertains to make and use the same, reference being had to the accompanying drawings, which form a part of this specification.

Sewing machines are now generally equipped with devices on which bobbins may conveniently be wound, the winding being automatically stopped whenever a bobbin has been filled to a predetermined point. These winding devices are provided with wheels or pulleys adapted to be driven frictionally either through contact with one of the usual or a supplementary wheel on the sewing machine or by contact with the driving belt. In the ordinary foot-power sewing machine, the forward run of the belt is approximately vertical; the inclination of the belt being changed somewhat where a motor is placed underneath the table of the machine. However, when the motor is placed behind the sewing machine head, as is the general practice in so-called portable sewing machine heads, that part of the belt passing down from the front side of the driven pulley on the head no longer extends in the vertical direction but is inclined sharply toward the rear; the result being that the ordinary belt-driven bobbin winder attachment cannot be employed.

The object of the present invention is to produce a simple and novel bobbin-winding device which will permit a bobbin, arranged in the usual way on the front side of the sewing machine, to be conveniently driven from the belt driven by a motor lying behind the head.

The various features of novelty whereby my invention is characterized will hereinafter be pointed out with particularity in the claims; but, for a full understanding of my invention and of its object and advantages, reference may be had to the following detailed description taken in con-

nnection with the accompanying drawing, wherein:

Figure 1 is an end view of a sewing machine head mounted on a portable base and having thereon a bobbin winder arranged in accordance with the present invention; and

Fig. 2 is a side view, on a larger scale, of the bobbin winder device detached from the head, this figure showing the opposite side of the device from that which appears in Fig. 1.

Referring to the drawing, 1 represents a sewing machine head having a driven pulley, 2. In rear of the head and mounted on the same base, 3, as that on which the head is mounted, is an adjustable motor, 4. A belt, 5, passes around a driving wheel or pulley, 6, on the motor and around the driven wheel 2 of the sewing machine. The motor is mounted in such a manner that it tends constantly to swing or otherwise move in a direction to tighten the belt, thus at all times maintaining the belt under tension. This may conveniently be accomplished by pivotally supporting the motor so as to permit it to swing about an axis or shaft, 7, parallel with the axes of the wheels 2 and 4; a suitable spring, 8, being provided for the purpose of constantly exerting a force on the motor tending to swing the pulley 6 rearwardly and away from the driven pulley of the machine.

The bobbin-winding device comprises a bracket, 9, attached to a stationary part of the sewing machine head by means of a screw, 10, or in any suitable way; the bracket carrying at its front end a complete winding device of any usual or suitable construction. In the arrangement shown, the winding device consists of an arm, 11, pivotally connected at its lower end to the front end of the bracket and carrying at its upper end a horizontal rotary bobbin-receiving shaft or spindle, 12, to one end of which is secured the winder pulley, 13. A spring, 14, tends constantly to swing the upper end of the arm toward the operator. A catch, 15, is adapted to engage with a shoulder, 16, on the swinging arm to lock the latter in a working position; the catch being provided with a finger, 17, which extends upwardly past the shaft or

spindle, 12, in position to be engaged by the thread in a bobbin wound upon the spindle and to cause the catch to be tripped when a sufficient amount of thread has been 5 wound.

On the bracket behind the swinging arm and in the same plane as the winder pulley is an idler pulley, 18, so positioned that when the front run of the driving belt is 10 passed underneath the idler pulley, that part of the belt lying between the idler pulley and the driven wheel or pulley 2 of the sewing machine, indicated at 19, occupies the proper position to permit the winder 15 pulley to be brought into driving engagement therewith in the usual way when the parts occupy their winding positions as illustrated in the drawing.

It will therefore be seen that I am enabled 20 to employ a bobbin winder located in the place where bobbin winders are usually placed and adapted to stop winding when the bobbin is full, and at the same time permit it to be driven from a belt leading to 25 a motor lying behind a sewing machine head.

During the time when no winding is to be done the belt may be slipped off the idler pulley and be permitted to run directly between the driving and driven pulleys; the parts being so proportioned that the slack in the belt is taken up by an automatic shifting of the spring pressed motor about its pivotal support. Consequently it is only a 35 matter of shifting the belt upon or from the idler pulley, no other adjustment being necessary since the slack in the belt is automatically taken up and again automatically provided when needed.

40 While I have illustrated and described with particularity only a single preferred form of my invention, I do not desire to be limited to the exact structural details thus illustrated and described; but intend to 45 cover all forms and arrangements which

come within the terms employed in the definitions of my invention constituting the appended claims.

I claim:

1. The combination with a sewing machine head, of a motor arranged behind the head, a driving belt between the motor and the head, a bobbin winder arranged at the front of the head and having a winder pulley, and a guide associated with said bobbin winder and engaging with said belt to deflect the latter into engagement with said winder pulley when the latter is in its winding position. 50

2. The combination with a sewing machine having a driven pulley, of a motor provided with a driving pulley, a belt passing over said pulleys, a bobbin winder having a winder pulley lying remote from the lower run of the belt when the latter extends in a straight line between the driving and driven pulleys, and an idler pulley associated with said bobbin winder and deflecting said run of the belt to bring a part thereof into operative relation to said 65 winder pulley. 60

3. The combination with a sewing machine having a driven pulley, of a motor provided with a driving pulley, a belt passing over said pulleys, a bobbin winder having a winder pulley lying remote from the lower run of the belt when the latter extends in a straight line between the driving and driven pulleys, an idler pulley associated with said bobbin winder and deflecting said run of the belt to bring a part thereof into operative relation to said 75 winder pulley, and means for movably supporting said motor so as to permit it automatically to adjust itself to take up the slack 80 in the belt when the latter is unshipped from the idler pulley. 85

In testimony whereof, I sign this specification.

GEORGE H. RIDDELL.
